GRINDING AND POLISHING MACHINE

Lad L. Hercik, Lakewood, Ohio, assignor to The Hill Acme Company, Cleveland, Ohio, a corporation of Ohio

Application June 20, 1941, Serial No. 398,886

23 Claims. (Cl. 51—137)

This invention relates to abrading apparatus of that type in which the abrading element comprises a flexible rapidly travelling abrasive belt coated on one face with suitable abrading material. In machines of this type the belt is usually mounted on a plurality of rolls or pulleys one of the rolls being the driving roll causing the belt to travel and another of the rolls being the contact or pressure roll serving to engage the rapidly travelling belt with the work to be treated in the machine. This work, in machines of this type is usually moved past the contact roll on a suitable work support substantially juxtaposed to the contact roll, suitable means being provided for applying pressure between the abrasive belt and the work.

While the herein disclosed invention is adapted for use in many types of grinding, surfacing and polishing machines and while it may also be adapted for producing or treating surfaces on many types of material, this invention is particularly well adapted for use in machines intended for removing scale from or for abrading or grinding or polishing or otherwise treating surfaces on relatively thin flexible sheets or strips of material. This invention is accordingly illustrated and described in an embodiment in a machine adapted for grinding and/or polishing relatively thin sheets or strips of steel, stainless steel, Monel metal, zinc, bronze or other metallic or non-metallic materials either in continuous lengths such as may be designated as "strip sheets" or in relatively shorter sheets.

As is well known to those skilled in this art, it has been very difficult to produce a ground or polished surface on sheets or strips, which is uniform, smooth and free from irregularities of finish. This has been due partly to the chatter like vibrations imparted to the machine by the plurality of necessarily high speed pulleys, shafts, and other rapidly rotating elements supported on the housing of the machine, partly to the irregularities rapidly developed in the surface of the abrading belt by the severe treatment to which the belt is exposed in the machinery at present developed, and partly by the flapping of the relatively long unsupported portions of the rapidly moving non-homogeneous abrasive belt.

It is well known that the best grinding results in machines of this type are obtained by the use of a contact or pressure roll of relatively small diameter for holding the belt in engagement with the travelling sheet to be finished. Due to the fact that, in previously known machines, the

two strands of the abrading belt have generally been either approximately parallel or have been inclined to each other at an acute angle, this small contact roll has produced a severe bend in the belt at the contact roll, tending to elongate the outer periphery of the belt and to crack the abrading surface and to break the bond between the abrading material and the belt, thus causing the abrasive material to loosen or flake off or form objectionable projecting ridges. As a result of the necessarily high peripheral speed of the belt, approaching velocities of 4000 feet per minute, there is a tendency of the belt to spring away from the contact roll and hence, in previously known machines of this type, considerable tension has been applied to this belt to insure a snug and accurate engagement of the belt with the face of the contact roll thus subjecting the belt to severe strains. As is also known, the driving roll usually is not made materially larger than the contact roll and a heavy strain or tension must be applied to the belt to prevent the slipping of the belt on the drive roll and to prevent the belt wearing, belt heating, belt jerking, and accompanying belt deterioration and machine vibration which results from such slipping. In order to provide ample resilience in the belt, a relatively long belt has heretofore been provided which was mounted upon terminal pulleys spaced proportionately far apart. This arrangement has resulted in relatively long lengths of unsupported belt which have tended to flap or whip thus introducing additional vibration into the machine. All of the above circumstances contribute to the introduction of irregularities in the appearance of the finish formed on the surface of the sheets.

One of the general objects of this invention, therefor, is to provide apparatus of this class which will produce an even, uniform and smooth finish upon strips or sheets and the like, which finish will be free from irregularities, blemishes or defects resulting from the imperfect functioning of the apparatus or abrading belt.

Another object of this invention is to produce a machine of this type in which the number of rapidly rotating parts are reduced to an absolute minimum and which will accordingly be free from the cumulative chatter producing vibrations resulting from a plurality of rapidly rotating parts.

A further object is to produce an arrangement of abrasive belt pulleys in a machine of this class which will eliminate the imposition of severe and destructive bending strains on the belt

thereby lengthening the efficient life of the belt and eliminating the loss of production resulting from delays incident to frequent renewals of the belt.

A further object is to provide a machine of this class in which a minimum of tension is required to be applied to the abrading belt to prevent continuous or intermittent slipping of the belt on the driving pulley.

A further object of this invention is to produce a grinding machine of this type in which the abrading belt is supported exclusively by one driving pulley and one driven pulley or roll and in which the unsupported lineal length of the strands of belt between the pulley peripheries is reduced to such a minimum that substantially no perceptible flapping or whipping occurs.

A further object is to produce a machine of this type in which a relatively large proportion of the length of the abrasive belt is continuously being cooled by engagement with the periphery of one of the pulleys on which the belt is mounted.

A further object is to produce apparatus of this type in which the pulleys are so constructed and mounted that a minimum of belt guiding and/or centering correction is required after the belt has once been properly centered.

A further object of this invention is the provision of a simplified mechanism for controlling the guiding and/or centering of an abrading belt travelling over a pair of spaced pulleys without the use of an auxiliary guiding or control roll or pulley.

A further and more specific object of this invention is the provision of an improved mounting for the head or driving pulley for an abrasive belt in which this pulley is tiltably mounted for the purpose of guiding or controlling the path of the belt, the mounting being adapted to be readily actuated by a controlling device responding to the deviation of the belt from a desired path.

A further specific object is the provision of an improved mounting of the drive pulley on its shaft to insure the accurate centering of the pulley on the shaft and to facilitate the mounting of the pulley on the shaft or the demounting of the pulley from the shaft.

A further understanding of the construction and operation and of the manner in which the novel features of this invention effect the above and further objects, will become apparent from the following detail description and the annexed drawings, which set forth certain means embodying this invention, such disclosed means constituting, however, but one of the forms in which the principle of this invention may be applied.

Referring to the annexed drawings:

Fig. 1 is a side elevation of a grinding and polishing machine embodying this invention, this disclosed machine being shown in an adaptation for grinding and/or polishing continuous metallic sheet strips, this view of the machine being taken from the operator's side of the machine and being partly broken away to show certain interior constructions.

Fig. 2 is a diagrammatic view illustrating, detached from the machine, certain elements of the mechanism for controlling the path of travel of the abrasive belt and including a wiring diagram and piping diagram disclosing the cooperative relation between the elements.

Fig. 14 is a plan sectional view taken thru the axis of the head shaft on the plane indicated by line 14, 14 in Figures 6 and 8.

Fig. 15 is a fragmentary sectional view thru the hub and head shaft of the head pulley, this view being an enlarged view of a portion of Figures 6 and 14.

General features of machine

The main portions of this improved grinding and polishing machine may be indicated briefly in general terms as follows:

The base supporting the operating mechanism of the machine is indicated at 1. On this base is mounted the work supporting mechanism which includes a vertically and horizontally adjustable billy roll 4. Also mounted on the base 1 is a column 22 upon which is mounted a head frame or housing 25, this housing being vertically adjustable on the column by means of a head frame adjusting mechanism including a screw 36 and associated power driven mechanism. Rotatably mounted in suitable bearings 42 and 46 in the head frame is a head shaft 50 upon one end of which is mounted a power pulley 60 and upon the other end of which is mounted, in an improved manner, a head pulley 64. A suitable power drive actuated by a motor 81 rotates the power pulley, head shaft and head pulley. This machine further includes a contact pulley 89 mounted on suitable supports secured to the base 1. An abrasive belt 90 is mounted on the head pulley 64 and contact pulley 89. Of the two bearings supporting the head shaft 50, one bear-

ing 42 serves as a fixed pivot about which the head shaft may be tilted and the other bearing 46 is shiftably mounted so as to provide a means for tilting the head shaft and the head pulley, this provision being made for the purpose of correctly guiding the abrasive belt 90 in the desired path of travel. Suitable mechanism for shifting the bearing 46 and thus tilting the head shaft 50 is provided in the fluid cylinder 111 actuated by a valve 132 and a suitable device for controlling the valve is provided by the air jet control unit indicated in its entirety at 144, which unit controls the valve and cylinder responsive to lateral deviations in the path of the abrasive belt. Brake mechanism including a brake drum 162 and brake shoes 165 is provided for rapidly stopping the rotation of the head pulley and abrasive belt.

The construction of the above enumerated features will now be described in detail. For purpose of reference in the following description, the operator's side of this machine, that is the side on which the head pulley is mounted, is designated as the "near side," and the side on which the power pulley is mounted is designated as the "far side" of the machine. Also for convenience of reference, the right end of the machine as viewed in Figures 1, 8 and 14 is designated as the "front" of the machine, and the left side of the machine as viewed in these figures is designated as the "rear" of the machine.

Work supporting mechanism

Referring first to Figures 1, 6, 8 and 14 of the drawings, the base of the machine is indicated at 1, this base being of suitable proportions to support the working parts of the machine and being constructed of any suitable material and in any desired manner as by welding or casting. Upon this base are mounted a pair of stands 2, 2 upon which are mounted bearings 3, 3 these bearings in turn rotatably supporting a work support in the form of a billy roll 4 of suitable diameter and width to accommodate the widest sheet for which the machine is designed. The billy roll 4 is adapted to be adjusted horizontally in the direction of travel of the work, that is, to the left or to the right as viewed in Fig. 1. This longitudinal adjustment is made possible by slotting the openings in the flanges of the bottom of the stands 2 by means of which these stands are bolted to the base, as will be readily understood from the indication at 5, 5 in Fig. 1. Each of the stands 2 may be adjusted individually in order that the axis of the billy roll may be positioned in parallel relation to a certain contact pulley 89 hereinafter to be described.

The billy roll 4 is also mounted for vertical movement toward and from the contact roll 89 and for this purpose the billy roll bearings 3 are each provided with a base 6 which is slidably mounted in openings 7 formed in the upper portion of the stands 2 as best appears in Figures 1, 6 and 14. The bases 6 are each formed with centrally disposed bosses in which are mounted the upper ends of piston rods 8. These piston rods are each mounted for vertical reciprocation preferably by means of fluid actuated pistons 9 mounted in cylinders 10. The pistons 9 are simultaneously actuated by means of suitable valve devices of any approved design simultaneously supplying and releasing fluid under pressure to and from inlets and outlets in the cylinders 10.

As clearly appears from Figures 1 and 6, the

piston rods 8 are provided with collars 11 adapted to about the lower end of vertically adjustable bushings 12, mounted in housings 13 centrally disposed within the stands 2. The engagement of the collars 11 with the lower end of the bushings 12 limits the upward movement of the piston rods 8 and thus fixes the upper position of the bearings 3 and hence the billy roll 4.

It will be evident that the upper position of the billy roll must be adjustable to accommodate various thicknesses of the work, various diameters of the contact roll 89, etc. For this purpose the bushings 12 are made vertically adjustable in order that collars 11 on the piston rod 8 may engage the bushings at different vertical positions thereby to stop the bearings 3 and billy roll 4 in the desired upper position. For purposes of adjustment, the bushings are provided at their lower ends with threads 14 engaging similar threads formed in the housings 13. At their upper ends the bushings are formed with spiral teeth 15 adapted to be engaged by worms 16 mounted on a worm shaft 17 which is in turn rotatably mounted in bearings in the housings 13. The worm shaft may be rotated by means of a hand wheel 18 (Fig. 14). It will be apparent that a rotation of the worm shaft will cause the worms 16 and hence the bushings 12 to rotate and this rotation will cause the bushing to advance upwardly or downwardly depending upon the direction of rotation. By this means the upper position of the billy roll 4 may be adjusted.

It is also essential that an independent vertical adjustment may be provided for each bearing 3 in order that the axis of the billy roll 4 may be disposed accurately parallel with the contact roll 89. In order to permit this independent vertical adjustment a coupling 19 (Fig. 6) is provided in the worm shaft 17 which, when disconnected, will permit the individual adjustment of each of the bushings 12 in order that the proper alignment of the axis of the billy roll may be obtained.

A strip or sheet of material to be finished in this machine is indicated at W and rides upon the upper surface of the billy roll 4 as clearly appears in Figures 1 and 6. This strip W is usually continuous and may be of any desired width within the capacity of the machine and may consist of steel, stainless steel, Monel metal, bronze, zinc, or other metallic or non-metallic materials which are to be ground, polished, satin finished, buffed or otherwise treated in this machine. It will appear that the strip W is deflected upwardly slightly about the billy roll and suitable auxiliary rolls may be provided for thus deflecting the strip W which rolls are well known and need not be shown and described. The strip is advanced over the billy roll 4 under a very high tension in order that the strip may be perfectly flat at the area at which it is being ground. The adjustability of the billy roll longitudinally of the strip makes it possible to position the billy roll to secure the most advantageous grinding engagement of the strip W with the abrasive belt 90 mounted on the contact pulley 89.

The devices for feeding and tensioning the strip are also well known and, as they form no part of this invention, are not shown. It is to be understood, however, that the strip feeding devices are presumed to be manually reversible under the control of the operator.

Column and head frame support

Supported on a pad 21 formed on the base 1 is

a preferably hollow rectangular column 22 as best shown in Figures 1, 6, 8, and 14. This column is formed with vertical ways 23 on the right side as viewed in Figures 1, 8 and 14. Intermediate the ways the column is formed with an elongated vertical recess or cavity 24.

Mounted in sliding engagement with the vertical ways 23 is a head frame or housing, indicated in its entirety at 25. This housing is formed with suitable sliding surfaces 26 adapted to seat upon the faces and sides of the ways 23. Guide or clamp bars 27, Fig. 14, are provided to hold the housing in sliding engagement with the ways. Suitable gibs may be provided to adjust the tightness of the sliding engagement of the housing on the column ways, as will be understood.

The upper end of the head frame or housing 25 is formed with a hollow generally semi-cylindrical portion 28 whose axis is disposed horizontally, that is, transversely of the ways 23 of the column. Forming a continuation of the portion 28 and extending laterally from the housing 25 toward the near or operator's side of the machine is a preferably tapered hollow portion 29. This portion 29 extends for a considerable distance laterally of the ways 23 and column 22, as best appears in Figures 6 and 14. The portion 29 is formed at its outer end with a recess 30 adapted to receive a bearing 42, to be hereinafter described. Adjacent the far side of the portion 28 the housing is formed with seat 31 upon which is mounted a bracket 32 which in turn supports a bearing 46 by means of mechanism to be described.

Formed adjacent the lower edge of the head frame 25 is an outwardly projecting lip 33 which supports a vertical plate 34 secured to the face of the frame 25 and serving as a base plate for the motor 31.

Head frame adjusting mechanism

Fixedly mounted on the rear face of the housing is a nut 35 engaged by a vertical screw 36 (Fig. 8). The lower end of this screw is supported in bearings 37 preferably mounted in the base of the column 22. Adjacent the lower end of this screw is mounted a worm gear 38 which is in turn driven by means of a suitably mounted worm 39. The worm 39 in turn is driven thru a pair of spur gears 40 by means of a motor 41. It will appear that the rotation of the screw 36 will advance the head frame upwardly or downwardly depending upon the direction of rotation.

Head shaft mounting

As will best appear from Fig. 7, the bearing 42 seated in the recess 30 at the near side of the extending portion 29 of the housing 25 comprises an outer race 43, anti-friction rollers 44 and an inner race 45. The bearing 46 horizontally movably mounted in the bracket 32 at the far side of the housing 25 comprises an outer race 47, anti-friction rollers 48 and an inner race 49. Mounted in the inner races 45 and 49 of the bearings 42 and 46 is a main or head shaft indicated in its entirety at 50.

The outer race 43 of the bearing 42 is clamped between a tongue formed on a cap 51 and a shoulder formed at the inner end of the recess 30, and is thus axially fixed with respect to the housing 25. The inner race 45 of the bearing 42 is fixed to the shaft 50 between a shoulder 52 formed on the shaft and a nut 53 having thread-

ed engagement with the shaft as will appear from an inspection of the left end of Fig. 7. It will accordingly be clear that the bearing 42 serves to axially fix the shaft 50 with respect to the housing 25.

The inner race 49 of the bearing 46 is fixed to the shaft 50 between a shoulder 54 formed on the shaft and a nut 55 having threaded engagement with the shaft, as will appear from an inspection of the right end of Fig. 7. The outer race 47 of the bearing 46, however, is axially slidably mounted in a cylindrical bore 56 formed in a bearing block 57 supported for horizontal shifting in the bracket 32 and as will appear, space is provided to permit such relative axial shifting.

The bearings 42 and 46 are each preferably of the self alining type which permit the limited angular tilt of the shaft with respect to the outer race and the bearing housing, this provision being made for a purpose to be herein-after pointed out.

Suitable enclosures and protective seals are preferably associated with the bearings 42 and 46 all as clearly shown on the drawings.

Power pulley on head shaft

At the far or right side, as viewed in Figures 6 and 7, the shaft is formed with a portion 59 extending outwardly toward the far side beyond the bearing 46 upon which a head shaft power pulley 60 is mounted, this pulley being fixed against rotation on the shaft by means of a key 61 and formed with a rim 62 to receive driving belts, as will be described.

Head pulley and mounting on head shaft

Extending outwardly toward the near side of the machine from the bearing 42 and extending thru the cap 51 and associated seal is an outwardly projecting portion 63 of the shaft 50 upon which is mounted a head pulley or abrasive belt driving pulley indicated in its entirety at 64. This pulley is formed with a hub 65 of substantially the same length as the shaft portion 63, which hub is mounted on the shaft portion in an improved manner to be later described.

The head pulley 64 comprises a plurality of webs indicated at 66, 67 and 68 supporting a rim or shell 69, as best appears from Figures 6 and 14. The webs 66 and 67 are positioned in radial planes adjacent the outer and inner ends of the hub 65 and the web 68 is principally conical and flares outwardly from the web 67 adjacent the hub toward the rim 69 to which it is connected. It is to be noted that the rim 69 is formed with a substantially straight face and is considerably wider than the length of the hub and that the rim is substantially aligned with the outer end of the hub at the near side of the machine and that the rim projects well beyond the inner end of the hub and overhangs not only the bearing 42 but also the section 29 of the housing 25 and, as will further appear from the drawings, the rim 69 is symmetrically disposed about the center of the bearing 42. The bearing 42 may accordingly be said to be disposed within the confines of the pulley 64 and is in fact preferably disposed substantially centrally of the face of this pulley.

It will be evident that the head pulley 64 being of relatively large diameter and wide face is necessarily of considerable weight and difficult to handle particularly in assembling upon and removal from the shaft end 63 upon which it is mounted. It is also to be noted that centering

of the head pulley on the shaft 50 and its axial alignment with the shaft must be perfect in order that the head pulley may run absolutely true and perfectly balanced, not only in the original installations but also in the event of a re-mounting or replacement of the pulley on the shaft. It is also evident that an extremely tight fit between the bore of the pulley and the shaft resulting in the adhering of the pulley to the shaft is seriously objectionable not only because of the difficulty of removing the pulley but also because of the danger of springing or distorting the shaft in assembling the pulley on the shaft or demounting the pulley from the shaft.

In order to facilitate the mounting and demounting of the relatively heavy head pulley 64 with respect to the shaft, an improved arrangement of parts is provided, which is best shown in Fig. 15. Referring to this figure, the outwardly projecting portion 63 of the head shaft 50 is formed outwardly beyond the bearing and preferably adjacent the sealing cap 51 on the head frame 25 with an outwardly converging conical portion 70 extending outwardly for about one third of the length of the hub 65 of the head pulley 64. Beyond the end of the conical portion 70 the shaft is formed with a cylindrical portion 71 extending outwardly to a point nearly flush with the outer end of the hub 65. Outwardly beyond the cylindrical portion 71, the shaft is formed with a threaded extension 72.

The bore of the hub 65 is formed at its inner end with an inwardly diverging conical surface 73 preferably accurately conforming to the surface on the conical portion 70 of the shaft. Outwardly of this conical surface the bore is formed with a slightly enlarged recess or chamber 74, and outwardly of the recess the bore is formed with a cylindrical portion 75, terminating in an outwardly diverging conical surface 76 extending to the outer end of the hub 65. The cylindrical portion 75 of the bore is slightly larger in diameter than the outside diameter of the cylindrical portion 71 of the shaft 50 to form a clearance which in practice need not necessarily be more than a few thousandths of an inch.

Mounted upon the threaded extension 72 is a collar or nut 77 having a threaded bore engaging the extension 72 and formed with an inwardly converging conical portion 78 accurately conforming to the outwardly diverging conical surface 76 in the hub of the pulley. The collar or nut 77 is additionally formed with a recess on its inner face, this recess being formed with a cylindrical surface 79 whose inner diameter is a relatively tight but rotatable fit on the outer diameter of the cylindrical section 71 of the shaft, which serves to accurately center the nut 77 on the shaft 50. The nut is provided with a suitable slot for turning.

A key 80 is preferably provided engaging suitable keyways in the shaft and pulley hub to serve as a means for rotatably fixing the pulley to the shaft.

In assembling the pulley 64 on the shaft 50 it will be apparent that the enlarged end of the outwardly diverging conical opening 73 in the hub 65 will readily pilot the pulley 64 on the shaft 50, whereupon the pulley is moved inwardly until the conical surface 73 of the hub is seated on the conical portion 78 of the shaft. The nut 77 is then screwed on the threaded extension 72 of the shaft, the nut being accurately axially centralized and aligned with the shaft by the engagement of the cylindrical surface 79 with the cy-

lindrical portion 71 of the shaft until its conical surface 78 engages the conical recess 76 in the hub. A further advancing of the nut will simultaneously force the inner end of the pulley hub into a firm seating position on the conical portion 78 of the shaft and will accurately centralize and axially align the outer end of the pulley with the shaft, thus insuring the rigid coaxial mounting of the pulley on the shaft.

When the pulley is to be demounted from the shaft, the nut 77 is backed off the threaded extension 72 to release the thrust against the pulley hub. The outer end of the pulley is then free to tilt downwardly toward the shaft to the extent of the limited clearance between the cylindrical bore 75 of the pulley hub and the cylindrical portion 71 of the shaft. If the pulley is so firmly seated on the conical portion 78 that it will not readily free itself, a slight tilting stress applied to the rim of the pulley aided, if necessary, by a slow rotation of the shaft will quickly effect the release of the pulley from the conical portion 73 whereupon the pulley may be removed by the use of a crane or other convenient facility.

It will be evident that the above construction readily permits the assembly and demounting of the pulley without any scoring or distorting of the mating parts and that the pulley may be demounted and reassembled frequently without affecting the accuracy of the mating parts and that a damaged or worn pulley may be replaced by a new pulley and that an accurate coaxial alignment of the pulley with the shaft is assured at each assembly.

Drive for head pulley

Mounted on the vertical plate 34 is an electric motor 81 this motor being secured to the plate 34 by means of bolts which have slotted engagement with the plate as shown at 82 in Figures 6 and 8. Adjusting screws 83 are mounted in any desired manner in the plate 34 and are adapted to adjust the position of the motor vertically with reference to the plate 34 and housing 25. Mounted on the motor shaft is a pulley 84 formed with a plurality of grooves. Mounted in the grooves 84 and on the rim 62 of the power pulley 60 are a plurality of V belts 85. It will appear that by this arrangement the rotation of the motor will be effectively transmitted to the head shaft 50 and pulley 64 without vibration. As will be understood, the proper tension may be imposed on the V belts 85 by suitable vertical adjustment of the motor by means of the adjusting screws 83.

Contact pulley and supports

As will best be understood from Figures 1, 6, and 14, a pair of spaced stands 86 formed with base flanges 87 are preferably fixedly mounted on pads formed on the base 1. Supported on the upper ends of these stands are anti-friction bearings 88, 88 in which is mounted in turn a contact pulley or roll 89. This contact pulley is accordingly fixedly mounted with reference to the base 1 and is substantially parallel to the head pulley and is below and slightly forwardly positioned with reference to the axis of the head pulley 64. It is to be noted, however, that the contact pulley is not positioned forwardly beyond the periphery of the head pulley, that is, the contact pulley is located between parallel vertical planes passing thru the axis of the head pulley and tangent to the periphery of the head pulley respectively, and as will also be evident, the

upper periphery of the contact pulley is substantially horizontally aligned with the lower periphery of the head pulley, this arrangement just pointed out producing a construction of the maximum compactness.

The axis of this contact roll as will appear from Figures 1 and 6, is spaced from and is positioned above and substantially parallel to the billy roll 4 in the normal position of that roll.

This contact pulley may be made of any suitable solid or laminated material but I have found that contact pulleys made of rubber, synthetic rubber or similar resilient materials are most efficient in service.

Abrasive belt and mounting

A flexible endless abrasive belt 90 is mounted on the head pulley 64 and contact pulley 89, this belt consisting of a paper or fabric base or backing material coated on the outer face with abrading or polishing material suitable for producing the type of finish desired on the work W. The relation between the head and contact pulley and their relation to the abrasive belt are considered essentially novel features of this invention and their relation may be pointed out as follows:

As will best appear from reference to Fig. 1, the diameter of the contact pulley 89 is less than one sixth of the diameter of the head pulley 64 and I find that the best results are obtained with a diameter ratio for these pulleys of substantially one to eight. As will also be clear, the head pulley and the contact pulley are spaced extremely close together, so close together in fact that the axes of the head and contact pulley are spaced from each other a distance less than the diameter of the head pulley. I have further found it desirable to space the periphery of the contact pulley close to the adjacent portion of the periphery of the head pulley and for this reason I prefer to space the peripheries of the head and contact pulleys apart a distance substantially equal to or less than the diameter of the contact pulley.

As will appear from reference to Fig. 1, two portions of the abrasive belt 90 engage the peripheries of the head pulley and contact pulley, respectively, and two unsupported strands of abrasive belt 90a, 90a are intermediate the periphery engaging portions. As pointed out at the beginning of this specification, it is desirable to reduce the length of these unsupported strands to a minimum in order to avoid vibration resulting from flapping or whipping and it will appear that the unsupported length of each of the strands does not exceed 1½ times the length of the periphery of the contact pulley.

Reference to Fig. 1 will also disclose the fact that the included angle α between the unsupported strands 90a, 90a approximates 90° and is in fact substantially greater than 80°.

Reference to Fig. 1 will also disclose the fact that the abrasive belt 90 engages an extremely large portion of the periphery of the head pulley, the angle of contact being indicated at A and being actually in excess of 260°. This extensive area of contact between the abrasive belt and the head pulley insures an absence of slipping between the driving head pulley and the belt even when the tension on the abrasive belt is relatively low in intensity.

It is further to be noted that the abrasive belt becomes severely heated as a result of the abrading action between the belt and the work, thus

tending to deteriorate the belt. This heat is usually intended to be carried away by relatively long lengths of unsupported strands of the belt which are in contact with air. While these long, unsupported strands have certain disadvantages pointed out, it is also well known that air is a poor conductor of heat, and I have found that the long arc of contact of the belt with the head pulley makes possible a substantially complete abstracting of the heat from the belt due to the relatively high heat conductivity of the metal rim of the pulley, this rim being cooled by the air flowing centrifugally outwardly against the inner face of the rim. As will appear, well over 50%, 70% in the embodiment shown, of the total lineal length of the belt engages the periphery of the driving pulley.

It will appear that a proper tension may readily be applied to this belt by suitably vertically moving the housing 25 which in turn supports the head shaft 50 and head pulley 64, whereby the center to center distance between the head pulley 64 and relatively stationary contact pulley 89 may be varied.

This abrasive belt is preferably driven in the direction indicated in the drawings by arrows. As is well known, it is extremely difficult to maintain a web travelling in a fixed path when the web is travelling on straight or substantially straight pulleys unless the path of the web is controlled by suitable devices. This is particularly true in the case of abrasive belts in which differences of strength, thickness, pliability and other differences may initially be incorporated in the belt or in which such differences may progressively develop as the belt is being used due to changes in thickness or character of the abrading coating or backing. For this reason it becomes necessary in machines of the character described in this application to provide means for returning the belt to the desired path when it deviates from this path. Many and varying types of devices have been developed for controlling the path of such travelling webs, most of which devices include the provision of an auxiliary roll which is suitably manipulated to correctively guide the web, this roll being actuated by some type of a control device which is actuated responsive to deviations in the path of the travelling web.

The herein described embodiment discloses an improved method of guiding the abrasive belt in the desired path. This method consists of angularly tilting the head or driving pulley about a pivot point within the confines of the pulley, this pivot point being preferably located on the geometric center of the pulley. In the present instance this pivot point is located at the point C defined by the intersection of the axis of the shaft 50 and the radial plane passing thru the center of the self alining bearing 42. In the embodiment disclosed, the shaft 50 and hence the pulley 64 is tilted by displacing the axis of the shaft 50 horizontally in opposite directions from a normal position, the mechanism for effecting this horizontal tilt being controlled by an actuating device which responds to deviations of the belt from the normal path. The mechanism for horizontally tilting the head or driving pulley will now be described.

Head pulley tilting mechanism

As previously described, the shaft 50 is mounted in bearings 42 and 46, the bearing 42 being fixed in the housing 25 and serving as a pivot about which the shaft may be angularly tilted

and the bearing 46 being supported in a horizontally shiftable bearing block or housing 57. This block 57 is provided at its lower edge with a horizontal track member or race 91 supported on an anti-friction roller structure 92 which is in turn supported on a track or race 93 fixedly secured to the bracket 32 as best appears in Figures 7 and 9. Serving as an additional overhead guide for the bearing block 57 are a track or race 94 mounted along the top of the block, an anti-friction roller structure 95 and a race 96 secured to an upper horizontal wall of the bracket 32. As will be understood, the bearing 46 and the bearing block 57 and associated parts are readily shifted horizontally with a minimum of mechanical effort.

Fixed to the bearing block 57 at the rear end or left end of the machine as viewed in Figures 8 and 14, or on the right end as viewed in Fig. 9, is a pin 97 upon which is mounted a telescoping frame. This frame comprises upper and lower outer frame elements 98 and 99 which are mounted on the pin 97. Slidably engaging the elements 98 and 99 are upper and lower inner frame elements 100 and 101, which are mounted on a pin 102 parallel to and spaced from the pin 97, upon which pin 102 is also mounted the head of an eye screw 103. The shank of the eye screw is formed with a thread as indicated at 106 and is mounted for axial slidable movement in a pair of spaced bosses 104 and 105 formed on the bracket 32. Mounted on the shank of the eye screw and formed with a threaded bore engaging the thread 106, is a bevel gear 107. Meshing with this bevel gear is a bevel pinion 108 suitably mounted on a shaft rotatably supported in a boss 109 on the frame 32 and adapted to be rotated by any suitable manual or power means such as the hand wheel 110 shown adjacent to the boss 109 in Fig. 8, but which may be located at any position conveniently accessible to the operator.

Interposed between the pins 97 and 102 is a fluid actuated cylinder construction comprising a cylinder 111, having ears mounted on the pin 102 and a piston actuated rod 112 mounted upon the pin 97. The piston rod and cylinder are preferably axially aligned with the eye screw 103 and horizontally aligned with the shaft 50.

Integrally formed with and projecting upwardly from the upper outer telescoping frame element 98 and adjacent the respective ends of this frame element are ears 113 and 114 having aligned apertures in which are reciprocably mounted plunger rods 115 and 116. The upper inner frame element 100 is also formed with an upwardly projecting ear 117 this ear passing thru a slot or recess in the element 98 and projecting upwardly beyond the upper surface of the element 98 and being formed with an aperture aligned with the apertures in the ears 113 and 114 and adapted to support the adjacent ends of the plunger rods 115 and 116 as best appears in Fig. 13. Collars 118 and 119 are formed intermediate the ends of each of the plunger rods 115 and 116, these collars normally engaging the opposed faces of the ear 117. A spring 120 is interposed between the collar 118 and the ear 113 and a similar but slightly stronger spring 121 is interposed between the collar 119 and the ear 114, these springs serving to resiliently but firmly hold the collars 118 and 119 against the faces of the ear 117. The variation in the strength of the springs 120 and 121 is required in part to compensate for the unbalanced horizontal component of the tension of the abrasive and power belts. Nuts 122 and 123

having threaded engagement with the outer ends of the plunger rods are provided to suitably position the collars 118 and 119 with respect to the ears 113 and 114, as best appears in Fig. 13. The ear 117 is formed with a lateral offset portion 124, this offset portion being aligned with adjustable stop screws 125 and 126 mounted in bosses on the element 98 and serving to limit the movement of the screws 125 and 126 and hence the element 98 with respect to the element 100.

The lower elements 99 and 101 are each provided with ears, plungers, springs, and adjusting screws identical with those described with reference to the upper elements 98 and 100 as shown in the drawings.

The cooperation between the parts just described is as follows. The bosses 104 and 105 being integrally formed with the bracket 32 are fixed relatively to the housing 25. The eye screw 103 altho slidably mounted in the bosses 104 and 105 can be longitudinally fixed with respect to these bosses by the bevel gear 107 at any position within the range of the adjustment. Thus the pin 102 and the members 100 and 101 including the ears 117 can be longitudinally fixed with respect to the frame 32. The springs 120 and 121 are relatively stiff and are so selected that they will transmit any longitudinal movement or adjustment of the ear 117 to the ear 113 or to the ear 114 and thence to the elements 98 and 99 and thus to the pin 97 and to the bearing block 57. It is to be noted that the strength of the springs 120 and 121 is considerably greater than the resistance to horizontal movement offered by the anti-frictionally mounted bearing block 57. It will appear from the above description that a change in the longitudinal position of the eye screw 103 and pin 102 will produce a corresponding change in the horizontal position of the bearing block 57 and hence of the bearing 46 and of the far end of the shaft 50.

Assuming that the bearing block 57 has been located in the desired normal or neutral position in the manner described, if air is admitted to the cylinder 111 thru a suitable inlet 127 the piston 112a and piston rod 112 and pin 97 will be moved to the left as viewed in Fig. 9 thus positively moving the pin 97, elements 98 and 99 and bearing block 57 to the left and compressing the springs 121. The extent of this movement is limited, however, by the abutting of the stop screw 126 against the offset portion 124 on the ear 117 after which abutment no further movement of the piston can take place. This admission of air thru the inlet 127 accordingly causes a horizontal shift in the bearing 46 and in the far side of the shaft 50 to the extent permitted by the stop screw 126. As soon as the air pressure is released thru the opening 127, the spring 121 again expands until a condition of equilibrium is established between the springs 120 and 121 whereupon the parts will again have been returned to the positions shown in Figures 9, 10 and 13.

If, on the other hand, air pressure is admitted to the inlet opening 128, the piston 112a and piston rod 112 are moved toward the right as viewed in Fig. 9, causing the pin 97 likewise to move toward the right thus moving the bearing block 57 and the elements 98 and 99 toward the right. This movement causes the springs 120 to be compressed and causes the bearing 46 to move to the right (as viewed in Fig. 9) the extent of this movement being lim-

ited by the abutment of the stop screw 125 against the ear 117. Upon the release of the air pressure thru the opening 128 the parts will again resume the neutral positions shown in Figures 9 and 10 by the expanding action of the springs 120.

It will be evident from the above that if the passage of air to the cylinder is suitably controlled the piston in the cylinder 111 and hence the piston rod 112 will cause the bearing 46 to be horizontally shifted in either direction from its normal or neutral position. It will also be evident, particularly from an inspection of Fig. 14, that the shifting of the bearing 46 will cause the head shaft 50 and hence the head pulley 64, to tilt about the center *c* of the fixed or pivot bearing 42. This tilting will be clockwise or counterclockwise as viewed in Fig. 14 depending upon the direction of the actuation of the piston and piston rod 112.

The piston 112a in the cylinder 111 is preferably actuated by compressed air and is controlled by suitable valve mechanism controlling the passage of air from a suitable source of air pressure, one arrangement of this mechanism being illustrated in Fig. 2. In this figure, an air pressure supply tank is diagrammatically shown at 130 from which a suitable air inlet 131 leads to the four way solenoid actuated valve 132. From this valve a line 133 leads to the inlet opening 127 at the head end of the cylinder 111 and a corresponding line 134 leads to the inlet opening 128 at the piston rod end of the cylinder. Suitable air exhaust openings 135, 135 are provided in the air valve 132 to permit the air pressure applied to the piston to escape when the piston is to be returned to the neutral position or is to be reversed. This air valve may be of any well known standard design and since this valve per se forms no part of this invention it need not be described in detail.

Devices for controlling tilting mechanism

The control device for actuating the head pulley tilting mechanism will be best understood by reference to Figures 1 to 5, inclusive, and comprises electrically energized solenoids shown at 136 and 137 these solenoids being mounted in any convenient position on the frame of the machine, in suitable relation to the valve 132. Each solenoid 136 and 137 is provided with a vertically movable plunger indicated at 138 and 139, respectively. Also supported on the frame of the machine in suitable relation to the valve 132 and solenoids 136 and 137 is a pair of bell crank levers 140 and 141 each associated with one of the solenoids and adapted to actuate the four way valve 132 to introduce air under pressure into one or the other of the lines 133 or 134 running to the cylinder 111. As shown in the drawings, the solenoid 137 when energized is adapted to actuate the valve 132 to introduce air under pressure thru the line 134 and inlet 128 into the piston rod end of the cylinder 111 and the solenoid 136 when energized is adapted to introduce air under pressure thru the line 133 and inlet 127 into the head end of the cylinder.

The solenoids 136 and 137 are selectively and intermittently energized by a control device indicated in its entirety at 144 and including electric switches and circuits which are actuated in response to lateral deviations of the abrasive belt from a predetermined normal path.

The solenoid 136 is associated with the circuit

145 which is adapted to be energized by the switch 147 and the solenoid 137 is associated with the circuit 146 which is adapted to be energized by the switch 148, as appears in Figures 2 to 5 inclusive. The above described solenoid controlled valve mechanism and the control device 144 are in principal substantially similar to the corresponding elements disclosed in my pending application Serial No. 337,326 and the 10 herein disclosed control device is practically identical with the device illustrated in Figures 11 to 15 of that application, and need only be briefly described here. The present control device, like the earlier device just referred to is located 15 adjacent one edge of the travelling belt and is responsive to the movement of one edge only of the travelling belt and is preferably positioned generally symmetrically about this edge of this belt as will appear best from reference to Figures 2, 4 and 5 of the present application.

20 2, 4 and 5 of the present application. The mercury switches 147 and 148 are supported in a suitable casing 149 this casing being mounted on an air inlet tube 150 which is axially and rotatably adjustably mounted in a bracket 151 preferably supported from one of the contact pulley stands 86 as shown in Figures 1, 6 and 14. It will therefor be seen that this casing may be laterally shifted with respect to the belt to locate the control devices in various lateral positions corresponding to the desired or necessary location of the edge of the belt which is intended to actuate the devices. A set screw or other suitable means may be used for fixing the casing and tube 150 in the desired position.

35. The mercury switches 147 and 148 are each formed with two spaced contacts located at one end of an enclosing glass tube, these contacts maintaining the circuit open when the tube is tilted to position the mercury in that end of the tube opposite the contacts. These mercury switches are each mounted on a shaft pivotally supported in the casing preferably in anti-friction bearings. Also mounted on these shafts and at points on opposite sides outside of the 45 casing are control levers 152 and 153, the lever 152 being associated with the mercury switch 147 and the lever 153 being associated with the

mercury switch 148. The control levers in the embodiment shown, pass upwardly around the respective sides of the casing 149 and toward each other and toward the center of the casing as is best shown in Fig. 5. At the inner or adjacent ends, these control levers are each provided with a relatively light flat plate, vane or spoon, indicated at 154 and 155 respectively, adapted to serve as an abutment for spaced jets of air presently to be referred to. The levers 152 and 153 and vanes 154, 155 normally assume a position by gravity, each resting against a stop pin, this being the position occupied by the lever 152 and vane 154, as best appears in Fig. 3. Secured to the upper face of the casing 149 is an angle bracket having a vertically disposed wall 156 which is interposed between the belt 90 and

156 which is interposed between the belt 90 and the vanes 154 and 155. A pair of apertures 157 and 158 closely spaced and axially aligned with the vanes 154 and 155 respectively, are formed in the wall 156. A branch tube 159 is mounted on the air inlet tube 150 this branch having a portion substantially parallel to the wall 156 in which portion a pair of nozzles 160 and 161 are located, these nozzles being axially aligned with the apertures 157 and 158, respectively. Air under pressure is supplied to the inlet tube 150 and thence to the branch tube 159 this air issuing

from the nozzles in relatively fine streams which, unless obstructed, pass thru the apertures 157 and 158 and impinge against the vanes 154 and 155 and which have sufficient kinetic energy to overcome the slight force of gravity acting on the vanes and associated parts thus tilting the associated vanes, levers and mercury switches from the position which they normally occupy by gravity.

As will appear, the nozzles are positioned adjacent the rear or smooth face of the belt, that is on the opposite side of the abrasive belt from the wall 156 and vanes 154 and 155, and are positioned to straddle the edge of the belt when the belt is travelling in the desired path, as clearly shown in Figures 2 and 4. As a result of the arrangement described, the air jet from the nozzle 160, in normal operation, impinges against the belt being thereby blocked from impinging against the vane 154 and thus permitting the vane 154 and associated lever 152 and switch 147 to assume the position which it normally occupies by gravity, while the air jet from the nozzle 161 passes past the edge of the belt thru the aperture 158 and impinges against the vane 155 thus displacing the vane 155 and associated lever 153 and switch 148 from the position which it would normally occupy by gravity. The terminals in the mercury switch 147 are so positioned that the circuit controlled by the switch 147 is open when the switch and vane are in position shown in Fig. 3, that is the position which they occupy by gravity. The switch 148, on the other hand, is so arranged that the circuit controlled by the switch is open when this switch and vane are in the position shown in Fig. 3, that is when the associated air jet 161 is impinging against the vane.

It is to be noted that two stop pins are provided on each side of the casing 149 to serve to stop the levers 152 and 153 in the desired terminal positions as best illustrated in Figures 3 and 4. Both of the switches 147 and 148 are arranged to close the respective circuits controlled by them when the switches are respectively in the alternate positions from those shown in Figures 1 to 5, that is when the lever 152 is forced against the right hand pin and when the lever 153 is resting by gravity against the left hand pin as viewed in Fig. 3. The wall 156 is provided primarily to protect the delicate vanes and control levers from serious damage in the event of a tear or break in the abrasive belt.

Head pulley brake

The momentum of the head pulley due to its large size and comparatively rapid rotation is relatively great and due to the anti-friction mounting of its shaft normally continues to rotate for a substantial period of time after the power is shut off. In order to eliminate the disadvantages incident to this prolonged rotation, and in order to provide a means for rapidly stopping the head pulley in an emergency, a suitable brake mechanism is provided.

This mechanism as best appears in Figures 6 and 8 consists of a brake drum 162 provided on the power pulley 60 and a bracket 163 mounted on the horizontal shiftable bearing block 57 and supporting a pin 164 upon which are mounted the lower ends of a pair of brake shoes 165, 165. These shoes are adapted to be moved into braking engagement with the inner face of the drum by means of a suitable air cylinder 168.

interposed between the upper or movable ends of the brake shoes. As will be understood, the suitable application of air pressure to the air cylinder 166 causes the shoes to expand into engagement with the inner face of the drum and the rapidity of braking will be proportional to the intensity of pressure applied to the cylinder 166.

Operation of grinding mechanism

The operation of the grinding mechanism of this improved machine will readily appear from the preceding description and from the drawings, supplemented by a brief further explanation.

15 In the drawings, the machine is shown in a non-operating or non-grinding position but the parts of the machine are assumed to be in correctly adjusted positions ready for proper operation and the parts are further assumed to be in motion just preliminary to the actual grinding. It is accordingly assumed that the strip W to be ground has been properly centered on the billy roll 4 and that it has been properly tensioned and that it has been caused to travel in the direction indicated in Fig. 1. It is further assumed that the abrasive belt 90 has been properly mounted on the large head pulley 64 and on the contact pulley 89 and that the abrasive belt has been correctly tensioned by vertical adjustment of the head pulley and that the drive belts have been correctly tensioned by vertical adjustment of the drive motor 81 and that the motor has been started, causing the abrasive belt to travel in the direction indicated in the several views. It is also assumed that the head pulley has been properly angularly tilted with respect to the contact pulley to cause the abrasive belt to travel in the desired path, this tilting having been effected by the proper horizontal shifting of the bearing 46 by means of the mechanism and method described hereinbefore under the heading Head pulley tilting mechanism. It is also assumed that the billy roll 4 has been properly positioned horizontally and in parallel relation with reference to the contact roll 89 and that the bushings 12 have been accurately vertically adjusted to properly space the billy roll from the abrading belt to produce the desired thickness of the finished strip W, this being effected by means of the mechanism and in the manner hereinbefore described under the heading of Work supporting means.

means.

55 All of the elements of this machine having been properly adjusted and set in motion, as pointed out, air under pressure is simultaneously admitted to the cylinders 10 which cause the pistons 9, piston rods 8, bearings 3 and billy roll 4 to move upwardly to the predetermined position in which the collars 11 on the piston rod 8 engage the bushings 12 thus causing the travelling strip W to be positioned in proper grinding relation to the abrasive belt.

60

65 The character of the finish produced by the abrasive belt can immediately and clearly be inspected as soon as it emerges from the grinding area this being made possible by the substantially vertical approach of the abrasive belt toward the work. If the depth of the grinding is too great or not sufficiently deep, corresponding adjustments can be made by the operator while the grinding is progressing by suitably turning the hand wheel 30. Means may also be provided to 70 instantly reverse the direction of travel of the

strip W in the event that the initial grinding has not completely eradicated surface defects and a local or complete re-grinding is necessary.

When the grinding of the strip has been completed or when it is desired to interrupt the grinding operation for any other reason, it is only necessary for the operator to release the air pressure from the lower faces of the pistons 9 in the cylinders 10 whereupon the billy roll 4 and the strip W, drop, aided by air pressure on the upper face of the piston, if necessary, to the position spaced from the belt as shown in the drawings. If it becomes necessary or desirable to quickly stop the rotation of the head pulley 64 this can be effected by applying air pressure to the air brake cylinder 166 in the head pulley brake as hereinbefore explained.

Operation of belt guiding mechanism

In the position of the parts as shown in the drawings, the abrasive belt is assumed to be running in the desired predetermined path. In this position of the belt the nozzles 160 and 161 are positioned to straddle the edge of the belt as clearly shown in Figures 2, 4 and 5. Accordingly the air jet from the nozzle 160 impinges against the belt 90 and is blocked from reaching the vane 154 thus permitting the lever 152 to gravitationally hold the switch 147 in the open position. The air jet from the nozzle 161 on the other hand, clears the edge of the belt 90 and impinges against the vane 155 thus displacing the lever 153 from its gravitational position and maintaining the switch 148 in the open position.

Under the above circumstance, that is when both switches 147 and 148 are open, both solenoids 136 and 137 are de-energized and the four way valve 132 is in the position in which it releases the pressure from both ends of the cylinder 111 and the spring controlled plungers 115 and 116 maintain the bearing 46 and hence the head shaft 50 and the head pulley 64 in the normal position thus tending to maintain the web travelling in the desired predetermined path, these spring controlled plungers 115 and 116 likewise causing the piston to assume an intermediate position between the ends of the cylinder 111.

As pointed out, however, the travelling belt is subject to lateral deviations from its desired path and the hereinbefore described head pulley tilting mechanism and control device constitute belt guiding mechanism intended to return the belt to its normal path of travel in the event that the web has meandered, for any reason, from the normal path and this is effected as follows:

Suppose it be assumed that the abrasive belt shifts toward the far side as viewed in Fig. 1, that is to the right as viewed in Figures 2 and 6. In this event, the edge of the web will approach the jet issuing from the nozzle 161 and will eventually intersect the path of this jet and interrupt or block this jet from reaching the vane 155 on the lever 153. Under these circumstances the vane 155 and lever 153 swing downwardly to the left by gravity, that is in a counterclockwise direction as viewed in Figures 2 and 3, being freed from the restraint of the jet. The downward positioning of the lever 153 causes the mercury switch 148 to close the circuit 146 which in turn energizes the solenoid 137. The energizing of this solenoid lifts the plunger 139, this in turn tilting the bell crank lever 141 to so actuate the four way valve 132 as to introduce air thru the line 134 into the piston rod end of the cylinder 111. This air pressure causes the piston 112a to move toward the head

end of the cylinder thus moving the piston rod 112, bearing block 57 and bearing 46 to the left as viewed in Figures 2, 8, and 14, that is, to the right as viewed in Fig. 9, and compressing the springs 120. This movement causes the far end of the shaft 50 to shift or tilt to the left as viewed in Fig. 14, this tilting or pivoting taking place about the center c of the bearing 42. This tilting of the head shaft causes a corresponding tilting of the axis of the head pulley with respect to the axis of the contact pulley and this counterclockwise shifting of the pulley about the center c as viewed in Fig. 14 tends to return the belt to its normal position, that is it tends to move the belt progressively toward the near side.

After this belt has travelled laterally toward the near side a sufficient distance to reach substantially its normal path, the jet issuing from the nozzle 161 will again be unblocked, that is it will again clear the edge of the belt and be free to impinge against the vane 155 on the lever 153, thus causing the switch 148 to move to the open position and thus de-energizing the magnet 137 whereupon the plunger 139 drops to permit the valve 132 to shift to its neutral position in which the air is released from both sides of the cylinder 111. The pressure against the piston having been released, the expansion of the springs 120 again shifts the bearing block 57 to the right as viewed in Fig. 14 and hence tilt the shaft 50 back to its normal running position and the head pulley will again be so positioned that the belt will continue to travel in the normal path. It is to be noted that the stop screw 125 limits the extent to which the shaft 50 is tilted during the corrective action.

If the belt should travel to the near side of the machine, that is to the left as viewed in Figures 2 and 6, it will unblock the jet issuing from the nozzle 160, thus permitting this jet to impinge against the vane 154 and tilt the lever 152 and switch 147 to a position in which the switch 147 closes the circuit 145 thus energizing the solenoid 136 causing the plunger 138 and associated bell crank 140 to actuate the valve 132 to introduce air under pressure thru the line 133 into the head end of the cylinder 111 which causes the bearing block 57 and the bearing 46 to move to the right as viewed in Figures 2, 8, and 14 thus compressing the spring 121 and shifting the far end of the shaft 50 toward the right and tilting the head pulley 64 in a clockwise direction, as viewed in Fig. 14, about the center c. This tilting causes the belt to progressively travel toward the far side. This tilted position is maintained until the belt has substantially reached its normal path at which time the jet issuing from the nozzle 160 is again blocked by the belt thus permitting the vane 154, lever 152 and switch 147 to tilt to the position in which the switch is open, thus de-energizing the solenoid 136 and thus controlling the valve 132 to permit the air to escape from the cylinder 111 whereupon the compressed spring 121 again shifts the bearing 46 to the normal position and tilts the head shaft 50 to its normal running position in which it normally maintains the belt travelling in the desired path.

It will be seen from the above description that the tilting of the head or abrasive belt driving pulley and the corrective shifting of the abrasive belt is initiated in response to any excessive deviation from the desired predetermined path of travel of the belt.

General

It will be evident that in the herein disclosed

belt type grinding and polishing machine the number of rapidly rotating parts has been reduced to an absolute minimum and that the proportionately very large head pulley reduces the objectionable vibration producing capacity of the rotating parts of this machine, and that the improved association of relatively very large and very small pulleys eliminates the destructive bending strains on the belt, and that the selection of the relatively very large driving pulley reduces the tension which must be applied to prevent the slipping of the belt, and the relatively close mounting of the large and small belt pulleys produces a very compact unit and eliminates belt whipping, and the tiltable mounting of the driving head pulley about a center within the confines of the pulley produces a simplified mechanism for the guiding and/or centering of an abrading belt traveling over a pair of spaced pulleys, and that this machine otherwise fulfills the objects set forth in the beginning of this specification.

Many modifications of this invention and its application will naturally occur to those skilled in this art and the present disclosure should therefore be considered as typical only, and I desire not to be limited to the exact constructions shown and described.

Inasmuch as this invention is unconcerned with the specific character of the work material or of the work-treating belt, the terms "abrasive" and the like, and "work" and the like, used herein and in the appended claims are intended broadly to include within their comprehension any and all materials to which the machine which constitutes this invention can be applied, as will be understood by those skilled in the art.

It is to be noted that certain features disclosed in this application and not claimed herein, are claimed in my co-pending application Serial No. 337,326 filed May 25, 1940, now Patent No. 2,274,268 of February 24, 1942 and in my co-pending application Serial No. 338,175 filed May 31, 1940, now Patent No. 2,316,582 of April 13, 1943.

What I claim is:

1. A machine of the character described including in combination, a driving pulley having a relatively large diameter, a contact pulley having a relatively small diameter, an endless abrasive belt mounted on said pulleys, the belt comprising two portions engaging the peripheries of the pulleys and maintained by the pulleys against vibration and two unsupported strands intermediate the periphery engaging portions, said unsupported strands being inherently subjected to vibration, the spacing of said pulleys being such that the length of each strand of unsupported belt does not exceed one and one half times the length of the periphery of the said contact pulley whereby the length of belt subject to vibration is kept relatively small, means for actuating the driving pulley, and a work support juxtaposed to said contact pulley.

2. A machine of the character described including in combination, a driving pulley having a relatively large diameter, a contact pulley having a relatively small diameter, an endless belt mounted on said pulleys and having bonded thereto an abrasive coating which tends to separate upon severe bending of the belt, the belt comprising two portions engaging the peripheries of the pulleys and two unsupported strands intermediate the periphery engaging portions, the included angle between the unsupported strands

being greater than eighty degrees whereby the bending stresses imposed on the belt by the contact pulley are kept within safe limits, means for actuating the driving pulley, and a work support juxtaposed to said contact pulley.

3. A machine of the character described, including in combination, a driving pulley having a relatively large diameter, a contact pulley having a relatively small diameter, an endless abrasive belt mounted on said pulleys, the belt comprising two portions engaging the peripheries of the pulleys so as to be cooled thereby and two unsupported strands intermediate the periphery engaging portions, the arc of contact of the abrasive belt on the periphery of the driving pulley being in excess of two hundred sixty degrees so that the cooling effect of said pulley on the belt is relatively great, means for actuating the driving pulley, and a work support juxtaposed to said contact pulley.

4. A machine of the character described, including in combination, a driving pulley having a relatively large diameter, a contact pulley having a relatively small diameter, an endless abrasive belt mounted on said pulleys, the belt comprising two portions engaging the peripheries of the pulleys so as to be cooled thereby and two unsupported strands intermediate the periphery engaging portions, the lineal length of the portion of the belt engaging the periphery of the driving pulley comprising more than fifty percent of the total lineal length of the belt so that the major portion of the belt is at all times cooled by said pulley, means for actuating the driving pulley, and a work support juxtaposed to said contact pulley.

5. In a machine of the character described, a supporting frame, a work support, a rotatable contact pulley juxtaposed to the work support, a head pulley rotatably mounted in the frame, an endless abrasive belt mounted on said pulleys, the diameter of said contact pulley being less than one sixth of the diameter of the head pulley, the axes of said pulleys being spaced from each other a distance substantially less than the diameter of the head pulley whereby the portion of the belt which is unsupported by engagement with said pulleys is rendered substantially small, power means for driving one of said pulleys, and means for moving the work support radially toward and away from the contact pulley so as to control the application of the portion of abrasive belt instantaneously on the contact pulley to work on the work support.

6. In a machine of the character described, a supporting frame, a work support, a rotatable contact pulley juxtaposed to the work support, a head pulley rotatably mounted in the frame, and endless abrasive belt mounted on said pulleys, the diameter of said contact pulley being less than one sixth of the diameter of the head pulley and the peripheries of the pulleys being spaced apart a distance less than substantially the diameter of the contact pulley whereby the portions of the belt which are unsupported by engagement with the pulleys are rendered substantially small and the included angle between said unsupported portions is relatively large, power means for driving one of said pulleys, and means for moving the work support radially toward and away from the contact pulley so as to control the application of the portion of abrasive belt instantaneously on the contact pulley to work on the work support.

7. In a machine of the character described, a supporting frame, a horizontal work support, a contact pulley juxtaposed to the work support and rotatable about a horizontal axis, a head pulley mounted in the frame for rotation about a horizontal axis, the diameter of the contact pulley being less than one-half of the diameter of the head pulley, the contact pulley being positioned between parallel vertical planes passing thru the axis of the head pulley and tangent to the periphery of the head pulley, respectively, the upper periphery of the contact pulley being substantially horizontally aligned with the lower periphery of the head pulley, an endless abrasive belt mounted on said pulleys, and power means for driving one of said pulleys, whereby the vertical spacing of the axes of the contact and head pulleys is reduced substantially to a minimum and the strand of belt extending to work issuing from the contact pulley is substantially vertical so that the effect of the belt on the work can be observed substantially at the line of contact between the work and the contact pulley.

8. A machine of the character described including, in combination, an endless abrasive belt, pulleys for supporting and driving the belt, said pulleys consisting of a driving pulley of relatively large diameter and a contact pulley of relatively small diameter and said belt comprising two portions engaging the peripheries of the pulleys and maintained by the pulleys against vibration and two unsupported strands intermediate the periphery engaging portions, said unsupported strands being inherently subject to vibrations, means for tilting the axis of one of said pulleys for correctively guiding the belt around said pulleys, the spacing of said pulleys being such that the length of each strand of unsupported belt does not exceed one and one half times the length of the periphery of the contact pulley, whereby the length of belt subject to vibration is kept relatively small, means for actuating the driving pulley, and a work support juxtaposed to the contact pulley.

9. A machine of the character described including, in combination, an endless abrasive belt, pulleys for supporting and driving the belt, said pulleys consisting of a driving pulley of relatively large diameter and a contact pulley of relatively small diameter and said belt having bonded thereto an abrasive coating which tends to separate upon severe bending, said belt comprising two portions engaging the peripheries of the pulleys and two unsupported strands intermediate the periphery engaging portions, the included angle between the unsupported strands being greater than eighty degrees whereby the bending stresses imposed on the belt by the contact pulley are kept within safe limits, means for tilting the axis of one of the pulleys for correctively guiding the belt around said pulleys, means for actuating the driving pulley, and a work support juxtaposed to said contact pulley.

10. A machine of the character described including, in combination, an endless abrasive belt, pulleys for supporting and driving the belt, said pulleys consisting of a driving pulley having a relatively large diameter and a contact pulley having a relatively small diameter and said belt comprising two portions engaging the peripheries of the pulleys so as to be cooled thereby and two unsupported strands intermediate the periphery engaging portions, the arc of contact of the abrasive belt on the periphery of the driving pulley being in excess of two hundred sixty degrees so that the cooling effect of said pulley on the belt

is relatively great, means for tilting the axis of one of the pulleys for correctively guiding the belt around said pulleys, means for actuating the driving pulley, and a work support juxtaposed to said contact pulley.

5 11. A machine of the character described including, in combination, an endless abrasive belt, pulleys for supporting and driving the belt, said pulleys consisting of a driving pulley of relatively large diameter and a contact pulley of relatively small diameter and said belt comprising two portions engaging the peripheries of the pulleys so as to be cooled thereby and two unsupported strands intermediate the periphery engaging portions, the lineal length of the portion of the belt engaging the periphery of the driving pulley comprising more than fifty percent of the total lineal length of the belt so that the major portion of the belt is at all times being cooled by said driving pulley, means for tilting the axis of one of the pulleys for correctively guiding the belt around said pulleys, means for actuating the driving pulley, and a work support juxtaposed to said contact pulley.

10 12. In a machine of the character described, a supporting frame, a work support, an endless abrasive belt, pulleys mounted on the frame for supporting and driving the belt, said pulleys consisting of a contact pulley juxtaposed to the work support and a head pulley, the diameter of the contact pulley being less than one sixth of the diameter of the head pulley, the axes of said pulleys being spaced from each other a distance substantially less than the diameter of the head pulley whereby the portion of the belt which is unsupported by engagement with said pulleys is rendered substantially small, means for tilting the axis of one of the pulleys for correctively guiding the belt around said pulleys, power means for driving the head pulley, and means for moving the work support radially toward and away from the contact pulley so as to control the application of the portion of abrasive belt instantaneously on the contact pulley to work on the work support.

15 13. In a machine of the character described, a supporting frame, a work support, an endless abrasive belt, pulleys mounted on the frame for supporting and driving the belt, said pulleys consisting of a contact pulley juxtaposed to the work support and a head pulley, the diameter of the contact pulley being less than one sixth of the diameter of the head pulley and the peripheries of the pulleys being spaced apart a distance less than substantially the diameter of the contact pulley whereby the portions of the belt which are unsupported by engagement with the pulleys are rendered substantially small and the included angle between said unsupported portions is relatively large, means for tilting the axis of one of the pulleys for correctively guiding the belt around said pulleys, power means for driving one of said pulleys, and means for moving the work support radially toward and away from the contact pulley so as to control the application of the portion of abrasive belt instantaneously on the contact pulley to work on the work support.

20 14. In a machine of the character described, a supporting frame, a head shaft, a pulley fast on one end portion of the shaft, a pair of spaced bearings rotatably supporting the shaft, a support for one of the bearings mounted for lateral movement with respect to the frame, the other bearing being pivotally mounted in the frame, said pivotally mounted bearing being interposed between the movable bearing and the fastening

for the pulley on the shaft, means for shifting the movable support, power means for rotating said shaft, a second pulley fixably supported relatively to the frame, an endless abrasive belt mounted on said pulleys, and work supporting means juxtaposed to one of said pulleys.

15. In a machine of the character described, a supporting frame, a head frame slidably mounted on the supporting frame, a shaft mounted in the head frame, a pair of spaced bearings rotatably supporting the shaft at points spaced from the ends of the shaft, a pulley adapted to support an abrasive belt mounted on one end of the shaft, a power receiving pulley mounted on the other end of the shaft, one of said bearings being disposed substantially centrally within the confines of the abrasive belt supporting pulley and the other bearing being disposed adjacent the power receiving pulley, and means for adjusting the latter bearing in a direction normal to the direction of sliding of the head frame.

16. In a machine of the character described, a supporting frame, an endless abrasive travelling belt, a pair of spaced pulleys about which the belt passes, said pulleys consisting of a contact pulley mounted on an axis fixably supported on the frame and a driving pulley, a shaft on which the driving pulley is fast, two bearings mounting the shaft on the frame, one being a pivot bearing disposed within the confines of the driving pulley, a slideable block mounting the other bearing for shifting the same to pivot the shaft about the pivot bearing, means connected to the slideable block to slide the same and thereby shift the path of travel of the belt, and work supporting means juxtaposed to the contact pulley.

17. In a machine of the character described, a supporting frame, an endless abrasive travelling belt subject to lateral deviations from a desired path of travel, a pair of spaced pulleys about which the belt passes, one of said pulleys being a contact pulley mounted on an axis fixably supported on the frame and the other of said pulleys being a driving pulley, a shaft on which the driving pulley is fast, two bearings mounting the shaft on the frame, one being a pivot bearing disposed within the confines of the driving pulley, a slideable block mounting the other bearing for shifting the same to pivot the shaft about the pivot bearing, control mechanism responsive to deviations of the belt from the desired path of travel connected to the slideable block for shifting the same, and work supporting means juxtaposed to the contact pulley.

18. In a machine of the character described, a supporting frame, an endless abrasive travelling belt, a pair of spaced pulleys about which the belt passes, one of said pulleys being a contact pulley mounted on an axis fixably supported on the frame and the other of said pulleys being a driving pulley, a shaft on which the driving pulley is fast, two bearings mounting the shaft on the frame, one being a pivot bearing disposed within the confines of the driving pulley and substantially centrally of the face of the driving pulley, a slideable block mounting the other bearing for shifting the same to pivot the shaft about the pivot bearing, means connected to the slideable block to slide the same and thereby shift the path of travel of the belt, and work supporting means juxtaposed to the contact pulley.

19. In a machine of the character described, a supporting frame, an endless abrasive travelling

belt, a pair of spaced pulleys about which the belt passes, one of said pulleys being a contact pulley mounted on an axis fixably supported on the frame and the other of said pulleys being a driving pulley, a shaft on which the driving pulley is fast, said shaft having a portion extending out beyond the frame, a power pulley on the end of said extending portion of the shaft having a driving belt engaged therewith, two bearings mounting the shaft on the frame, one being a pivot bearing disposed within the confines of the driving pulley, a slideable block mounting the other bearing on the portion of the frame adjacent to the power pulley for shifting said other bearing to pivot the shaft about the pivot bearing, means connected to the slideable block to slide the same and thereby shift the path of travel of the belt, and work supporting means juxtaposed to the contact pulley.

20. In a machine of the character described, in combination, a plurality of axially spaced shafts, a pulley mounted on each shaft including a driving pulley fast on its shaft, an endless abrasive belt mounted on said pulleys, a support for the driving pulley shaft adapted to permit the tilting of the shaft, means for correctively guiding the belt around said pulleys comprising mechanism for tilting the driving pulley shaft, means for driving the tiltable shaft, and brake means including a brake drum mounted on the tiltable shaft adapted when actuated to retard the rotation of the driving pulley, and manually controllable means for actuating the brake means.

21. In a machine of the character described, in combination, a plurality of axially spaced shafts, a pulley mounted on each shaft including a driving pulley fast on its shaft, an endless abrasive belt mounted on said pulleys, bearings mounting the driving pulley shaft including a shiftable bearing and a pivoted bearing, means for shifting the shiftable bearing so as to tilt the shaft about the pivoted bearing for correctively guiding the belt around said pulleys, means for driving the tiltable shaft, brake means including a brake drum mounted on the tiltable shaft adapted when actuated to retard the rotation of the driving pulley, and manually controllable means for actuating the brake means.

22. In a machine of the character described, in combination, an endless abrasive belt, a relatively large driving pulley and a relatively small contact pulley about which pulleys said belt passes, tiltable shaft means for supporting said driving pulley, power means for rotating said shaft means, and brake means including a brake drum mounted on the tiltable shaft adapted when actuated to retard the rotation of the driving pulley and manually controllable means for actuating the brake means.

23. In a machine of the character described, in combination, an endless abrasive belt, a relatively large driving pulley and a relatively small contact pulley about which pulleys said belt passes, a shaft fixed to the driving pulley and supporting the driving pulley, power means for rotating the shaft, means for rotatably supporting the shaft including at least one shiftable bearing, brake means interposed between the shaft and the shiftable bearing adapted, when actuated, to retard the rotation of the shaft and manually controllable means for actuating the brake means.
